UNITED STATES PATENT OFFICE.

HENRY RICE BUTTERFIELD AND WILLIS MITCHELL, OF WATERVILLE, MAINE.

ELECTRIC FLAT-IRON.

SPECIFICATION forming part of Letters Patent No. 424,404, dated March 25, 1890.

Application filed January 8, 1890. Serial No. 336,223. (No model.)

To all whom it may concern:

Be it known that we, HENRY RICE BUTTERFIELD and WILLIS MITCHELL, citizens of the United States, residing at Waterville, in the county of Kennebec and State of Maine, have invented certain new and useful Improvements in Electric Flat-Irons; and we do hereby declare the following to be a full, clear, and exact description of the invention, such as will enable others skilled in the art to which it appertains to make and use the same.

This invention relates to flat-irons which are heated by the action of a current of electricity; and it consists in the improvements hereinafter particularly set forth and claimed.

In the accompanying drawings, Figure 1 represents a side elevation of a flat-iron provided with our invention; Fig. 2, a vertical cross-section of the same, and Fig. 3 an end elevation of the same with the electrical devices removed.

A designates the hollow shell of the flat-iron, which is provided with a handle *a*, and has an opening *A'* in its broad end for the insertion of the wire coil *B*. This is wound about an insulated core *I*, which may be of copper or other metal, or of insulating material, and either solid, as shown, or hollow. The coils or layers of wire are preferably naked and separated from each other by strips *J*, of asbestos, slate, or other insulating material; or the wire may have an insulating coating throughout. We do not confine ourselves to any particular arrangement of said strips or to any way of winding said wires, but have shown them as preferred. Strips *K*, of insulating material, are interposed between the bottom of said coil and a copper plate *L*, which constitutes an inner lining for the bottom of the flat-iron shell *A*.

M designates an insulating-lining for the inner face of the sides and top of said shell. In the latter are clamping-posts *N N'*, to which the circuit-wires *O O'* are attached. These posts extend down through the top of shell *A* and insulating-lining *M*, and are in contact with the contact-plates *B'* on the ends of the wire *B*, so as to bring this wire into circuit with some generator of electricity for the purpose of evolving heat within said flat-iron. The core *I* gives solidity to the wire coil and makes it less likely to become disar-

ranged during the operation of introducing it into the flat-iron shell or withdrawing it therefrom. This coil may be secured in place within said shell in any conveniently detachable manner. The core, if of metal, becomes to some extent a reservoir of heat. If of iron, it also becomes a temporary magnet and may be incidentally useful for other than calorific purposes. The copper plate *L* facilitates the transmission of heat from the interior of the hollow flat-iron to and through the iron bottom of shell *A*, copper being an excellent heat-conductor. The heat is derived by the passage of the electric current through the wire coil (the latter, of course, offering resistance and being heated by said current) and the consequent excitement by radiation or otherwise of molecular motion in the hollow space surrounding it. This will be transmitted mainly through said copper plate. This plate *L* is preferably removable with said coil *B* and its core from shell *A*, the said plate constituting a slide or movable tray for said coil and core; or the said plate may be attached permanently to the said shell, the coil and core being removable independently of both shell and plate. The insulating-lining *M* is not removable if the electric connection is made as in Fig. 1; but said lining may be made removable without departing from the spirit or scope of my invention.

The plate *L* may be other material than that specified, since even asbestos will allow sufficient transmission of heat for the flat-iron to be serviceable, or said plate may be omitted; but a bottom lining which is a good conductor of heat is an improvement and very desirable.

Instead of the wire coil a different construction or material may be employed, this being necessarily a conductor of electricity, though offering resistance.

A heat-insulating covering *P* surrounds the upper part of the flat-iron to prevent radiation of heat into the air. This, however, is not necessary. A carbon filament or other resistance may be substituted for the wire *B*. The wire or filament may be wound in one layer or in successive layers, as shown.

Having thus described our invention, what we claim as new, and desire to secure by Letters Patent, is—

1. In combination with a hollow flat-iron shell, a removable conductor normally within the same and forming part of an electric circuit, for the purpose set forth.
5. 2. In combination with a hollow flat-iron shell, a removable coil of wire normally within the same and provided with a core on which it is wound, said wire being insulated by non-conducting material to prevent short-circuiting and forming part of an electric circuit, for the purpose set forth.
10. 3. In combination with a hollow flat-iron, an interior lining therefor and a conductor arranged within said lining, though removable from said flat-iron, the said conductor being in an electric circuit, for the purpose set forth.
15. 4. In combination with a hollow flat-iron, a lining of heat-insulating material for the inner face of the upper part thereof, a copper plate constituting a lining for the inner face of the bottom of said flat-iron, and a conductor of electricity arranged within the casting formed by said linings and adapted to be connected with circuit-wires, substantially as set forth. 25
20. 5. A hollow flat-iron, in combination with a removable interior lining and a conductor of electricity arranged within said lining and removable therewith, said conductor being arranged for connection with the circuit-wires of an electric circuit, substantially as set forth. 30
25. 6. In combination with a flat-iron, a coil of wire wound on a core and suitably insulated, said wire being adapted to become part of an electric circuit for the purpose of heating said iron, substantially as set forth. 35
30. 7. A flat-iron provided with a heat-insulating covering for its upper part, in combination with electric-heating devices, substantially as and for the purpose set forth. 40

In testimony whereof we affix our signatures in presence of two witnesses.

HENRY RICE BUTTERFIELD.
WILLIS MITCHELL.
